UNITED STATES PATENT OFFICE.

KARL F. G. GOETTING, OF ORANGE, NEW JERSEY, ASSIGNOR TO NEW JERSEY PATENT COMPANY, OF WEST ORANGE, NEW JERSEY, A CORPORATION OF NEW JERSEY.

DESIGN FOR A CABINET.

45,043.

Specification for Design.

Patented Dec. 16, 1913.

Application filed September 29, 1913. Serial No. 792,522. Term of patent 14 years.

To all whom it may concern:

Be it known that I, KARL F. G. GOETTING, a citizen of the United States, residing at Orange, in the county of Essex and State of New Jersey, have invented a new, original, and ornamental Design for Cabinets, of which the following is a specification, reference being had to the accompanying drawing, forming a part thereof.

The figure is a perspective view of a cabinet showing my new design.

I claim:

The ornamental design for a cabinet as shown.

KARL F. G. GOETTING.
